UNITED STATES PATENT OFFICE.

MOSES D. BLITZER, OF NEW YORK, N. Y.

DESIGN FOR A LIGHTING-BOWL.

49,109.

Specification for Design.

Patented May 30, 1916.

Application filed January 27, 1916. Serial No. 74,712. Term of patent 3½ years.

To all whom it may concern:

Be it known that I, MOSES D. BLITZER, a citizen of the United States, and a resident of the city of New York, borough of Brooklyn, in the county of Kings and State of New York, have invented a new, original, and ornamental Design for a Lighting-Bowl, of which the following is a specification, reference being had to the accompanying drawings, forming part thereof.

Figure 1 is a perspective view of a lighting bowl showing my new design; and Fig. 2 is an inverted plan view of the same.

The bowl-shaped body 10 of the lighting bowl is provided with a neck 11 having a raised band 12 ornamented with floreate

figures 13, and the bottom of the bowl appears with a central knob 14 from which radiate scallops 15 having a polygonal boundary 16. The space on the body 10 of the bowl intermediate the boundary 16 and the neck 11 is ornamental, with spaced representations of raised urns 17 linked together by raised garlands 18.

I claim:

The ornamental design for a lighting bowl as shown and described.

MOSES D. BLITZER.

Witnesses:

CHAS. A. GOTTESMAN,
CHARLES SHINSKY.
